CLEANING DEVICE FOR FLOORS AND THE LIKE
 Walter Carlson, 800 East B St., Iron Mountain, Mich.
 Filed Apr. 19, 1956, Ser. No. 579,251
 10 Claims. (Cl. 15—534)

This invention relates to cleaning devices for floors and the like which are adapted for use in applying a cleaning fluid and also for mopping or wiping up the cleaning solution or fluid.

The main objects of this invention are:

First, to provide a device for cleaning floors and other surfaces which may be used for applying a cleaning solution or fluid.

Second, to provide a device for cleaning floors and other surfaces which may be used for applying a cleaning solution or fluid to the surface and quickly adjusted for wiping the surface.

Third, to provide a cleaning device having these advantages which is highly efficient and may be rapidly manipulated for the purposes indicated with a minimum of manual effort.

Objects relating to details and economies of the invention will definitely appear from the description to follow. The invention is defined in the claims.

A structure which embodies the features of my invention is clearly illustrated in the accompanying drawing, in which:

FIG. 1 is a side elevational view of a cleaning device embodying my invention positioned as suspended from the handle.

FIG. 2 is an enlarged sectional view on a line 2—2 of FIGS. 3 and 4 in one position for use.

FIG. 3 is a transverse section on a line corresponding to line 3—3 of FIG. 2, the bail of the handle being partially broken away and shown in full lines.

FIG. 4 is a fragmentary plan view of the body member with the handle omitted.

FIG. 5 is an inverted perspective view of the sponge.

The embodiment of my invention illustrated is primarily designed for cleaning floors although it may be used to advantage for cleaning other surfaces. The device comprises a bottom 1 desirably having transverse ribs or corrugations 2. The outer side and end walls 3, 3 and 4, 4 project upwardly from the edges of the bottom. The inner side walls 5 and the inner end walls 6 and 7 are spaced from the outer side walls to define a channel-like reservoir 8 on three sides. The inner end wall 7 is spaced from the corresponding outer end wall a greater distance than the other inner walls to provide a reservoir enlargement or supply reservoir 9. The top wall 11 for the reservoir portion 9 is provided with a filler nipple 12, a closure cap 13 being provided with the nipple. The nipple is surrounded by a recess 14, the purpose of which will be later pointed out.

The inner walls define a rectangular holder adapted to receive the inner portion 15 of the sponge 16 which is preferably of synthetic material and is of substantial firmness. The sponge is provided with an outer portion 17 which overlaps the top walls and is supported thereby when the sponge is inserted in the holder. The flanges 18 project inwardly from the holder walls to retainingly engage the sponge which is desirably formed with grooves 19 receiving the flanges, although, being yieldable, the sponge may be retainingly engaged by the flanges without the groove being provided, but the grooving of the sponge to receive the flanges minimizes the likelihood of tearing the sponge as it is inserted and removed.

The ports or openings 20 are provided at the bottom of the inner walls 5 and 6 to feed cleaning fluid from the reservoir to the sponge. The bottom is adapted to receive and support the wiping cloth 21 which is arranged

2

across the bottom, preferably with some tension, and its ends wrapped around the ends of the body member and folded inwardly over the top walls which are provided with transverse grooves 22 in which the cloth is secured by the clamps 23.

The sponge is provided with a hole 24 receiving the filling nipple 12 when the sponge is positioned as shown in FIG. 2. The cap 13 is provided with a flange 25 which engages a substantial portion of the sponge around the opening therein and clamps it into the groove or recess surrounding the nipple with the cap or closure well spaced from the face of the sponge so that it does not contact the surface across which the sponge is manipulated.

The handle 26 is provided with a bail 27 having pintles 28 which are engaged in the outer side walls intermediate the ends thereof, preferably somewhat off center as is illustrated. The walls have bridging portions 29 constituting bearings for the pintles 28.

To facilitate quick return of the drainage from the sponge to the reservoir 9 when the device is positioned as shown in FIG. 1, the wall 7 is spaced from the bottom to provide a slot-like opening 30 and a baffle 31 is provided at the inner side of the wall 7 projecting upwardly from the bottom to prevent splashing or flow of the cleaning liquid through the slot-like opening 30 as the device is manipulated, either in the position shown in FIG. 2 or in the position shown in FIG. 3.

In the embodiment illustrated the body member is formed entirely of plastic and is molded in two sections, a juncture line being indicated by dotted lines. This permits the sections to be molded with the proper draft taper. The inner walls are desirably formed of one piece and that facilitates the forming of the ports or openings 20 in the inner walls.

It is contemplated that the device be used with a cleaning fluid as distinguished from water although it may be used with water. In manipulating the device the reservoir is supplied with cleaning fluid and is desirably left upright long enough for the sponge to become substantially saturated. The device is then manipulated across the surface to be cleaned and when an area thereof has been covered the device is inverted and manipulated with the wiping cloth downward to wipe up the previously treated surface. With the handle positioned as indicated, the device can be inverted by a flipping action at the same time the handle is positioned so desired pressure can be exerted with the device either side up. The device is highly efficient and a surface may be rapidly cleaned.

It will be noted that the openings 20 to the reservoir are positioned so that when the device is in position, shown in FIG. 2, the cleaning liquid cannot flow through the openings 20 as the device is manipulated as a result of sloshing of the liquid in the reservoir but when the device is

first put into use it should be positioned with the bottom 1 downwardly until a sufficient amount of liquid has penetrated the sponge. The device is then positioned as in FIG. 2 to apply the liquid to and scrub the surface and it may be readily reversed for drying or wiping the surface. The handle is so arranged that the device may be readily reversed to recharge the sponge although the reversal movement as commonly practiced in use results in keeping the sponge properly charged.

The device illustrated is elongated but it will be understood that it may be of any desired dimensions. The terms "side" and "end" walls are used for convenience and not as indicating dimensions; for example, the width might be greater than the front to rear dimensions.

The size of the device depends somewhat on whether it is designed for domestic use or for use in public buildings and the like where large areas are to be cleaned.

I have not illustrated various embodiments contemplated as it is believed this disclosure will enable those skilled in the art to embody the invention as may be desired.

Having thus described my invention what I claim as new and desire to secure by Letters Patent is:

1. In a cleaning device, a body member comprising a bottom transversely corrugated on its outer side, outer side and end walls, inner side and end walls spaced inwardly from corresponding outer walls, the inner walls defining a holder open at the top and having inwardly projecting flanges at their upper edges, top walls extending between said inner and outer walls and with said walls and bottom defining a reservoir surrounding the holder, the inner walls having openings at the bottoms thereof opening to said holder, one inner wall being spaced from its corresponding outer end wall to provide an enlargement for the reservoir, the top wall of which is provided with a filler nipple, there being a recess in the top wall surrounding said filler nipple, the end top walls having transverse grooves therein, a wiping cloth disposed upon the bottom with its ends wrapped around the outer end walls and disposed within said grooves, clamp members detachably securing said wiping cloth within said grooves, a sponge of substantial firmness having an inner portion disposed within said holder and an outer portion overlapping and in supported relation to said top walls, said inner portion having grooves in its edges with which said flanges are engaged, said outer portion having an opening therein receiving said filler nipple, and a closure threaded upon said filler nipple and clamping a portion of said sponge into said recess surrounding the nipple.

2. In a cleaning device, a body member comprising a bottom, outer side and end walls, inner side and end walls spaced inwardly from corresponding outer walls, the inner walls defining a holder open at the top and having inwardly projecting flanges at their upper edges, top walls extending between said inner and outer walls and with said walls and bottom defining a reservoir surrounding the holder, the inner walls having openings at the bottoms thereof opening to said holder, one inner end wall being spaced from its corresponding outer end wall to provide an enlargement for the reservoir, the top wall of which is provided with a filler nipple, there being a recess in the top wall surrounding said filler nipple, a sponge of substantial firmness having an inner portion disposed within said holder and an outer portion overlapping and in supported relation to said top walls, said inner portion having grooves in its edges with which said flanges are engaged, said outer portion having an opening therein receiving said filler nipple, and a closure threaded upon said filler nipple and clamping a portion of said sponge into said recess surrounding the nipple.

3. In a cleaning device, a body member comprising a bottom, outer side and end walls, inner side and end walls spaced inwardly from corresponding outer walls, the inner walls defining a holder open at the top, top walls extending between said inner and outer walls and with said walls and bottom defining a reservoir, the inner walls having openings to said holder positioned adjacent the top of the reservoir when the holder is facing downwardly, one top wall having a filler nipple and a recess surrounding the nipple, opposed top walls having grooves therein, a wiping cloth disposed upon the bottom with its ends wrapped around said opposed walls and disposed within said grooves, clamp members detachably securing said wiping cloth within said grooves, a sponge of substantial firmness having an inner portion disposed within said holder and an outer portion overlapping and in supported relation to said top walls, said outer portion having an opening therein receiving said filler nipple and a closure threaded upon said filler nipple and clamping a portion of said sponge into said recess surrounding the nipple, and a handle provided with a bail pivotally connected to the sides of the body member in spaced relation to its ends so that the body member is reversibly sup-

ported to permit the sponge or the wiping cloth being presented to a surface and to control the delivery of liquid to the sponge.

4. In a cleaning device, a body member comprising a bottom, outer side and end walls, inner side and end walls spaced inwardly from corresponding outer walls, the inner walls defining a holder open at the top, top walls extending between said inner and outer walls and with said walls and bottom defining a reservoir, the inner walls having openings to said holder positioned adjacent the top of the reservoir when the holder is facing downwardly, one top wall having a filler nipple and a recess surrounding the nipple, opposed top walls having grooves therein, a sponge of substantial firmness having an inner portion disposed within said holder and an outer portion overlapping and in supported relation to said top walls, said outer portion having an opening therein receiving said filler nipple and a closure threaded upon said filler nipple and clamping a portion of said sponge into said recess surrounding the nipple.

5. In a cleaning device, a body member comprising a bottom, outer side and end walls, inner side and end walls spaced inwardly from corresponding outer walls, the inner walls defining a holder and having inwardly projecting parts, top walls extending between said inner and outer walls and with said walls and bottom defining a reservoir surrounding the holder, the inner walls having openings to said holder, positioned adjacent the top of the reservoir when the holder is facing downwardly, one top wall having a filler nipple, a wiping cloth disposed upon the bottom, a sponge having an inner portion disposed within said holder and an outer portion overlapping and in supported relation to said top walls, said outer portion having an opening therein receiving said filler nipple and a closure threaded upon said filler nipple in clamping engagement with said sponge, and a handle provided with a bail pivotally connected to the body member so that the body member may be reversed and the sponge or the wiping cloth presented to a surface to control the delivery of liquid to the sponge within the holder.

6. In a cleaning device, a body member comprising a bottom, outer side and end walls, inner side and end walls spaced inwardly from corresponding outer walls, the inner walls defining a holder and having inwardly projecting parts, top walls extending between said inner and outer walls and with said walls and bottom defining a reservoir surrounding the holder, the inner walls having openings to said holder positioned adjacent the top of the reservoir when the holder is facing downwardly, one top wall having a filler nipple, a sponge having an inner portion disposed within said holder and an outer portion overlapping and in supported relation to said top walls, said outer portion having an opening therein receiving said filler nipple and a closure threaded upon said filler nipple in clamping engagement with said sponge.

33 7. In a cleaning device, a body member comprising a bottom, spaced inner and outer side and end walls, the inner walls defining a holder open at the top and having flanges projecting into the holder and being provided
60 with openings to the holder positioned adjacent the top of the reservoir when the holder is facing downwardly, top walls extending between said inner and outer walls, said bottom, inner and outer walls and top walls defining a reservoir, opposed top walls having grooves therein, a
65 wiping cloth disposed upon the bottom with its ends wrapped around said opposed walls and disposed within said grooves, clamp members for detachably securing the wiping cloth within said grooves, a sponge of substantial firmness having a portion disposed within said holder in
70 retaining engagement with said flanges and a portion overlapping said top walls, and a handle provided with a bail pivotally connected to the body member so that the body member is reversibly supported permitting the sponge or
75 the wiping cloth being presented to a surface and manipulated thereon by said handle.

8. In a cleaning device, a body member comprising a bottom, inner and outer side walls and top walls extending between the inner and outer walls and coacting therewith to define a reservoir, the inner walls defining a holder and having openings therein opening to the top of the reservoir when the holder is facing downwardly, a wiping cloth supportedly disposed upon said bottom, a sponge having an inner portion disposed in said holder and having an outer portion in overlapping supported relation to said top walls, and a handle pivotally connected to said body member whereby the body member is reversibly supported permitting either the sponge or the wiping cloth being presented to and manipulated upon a surface and to control the feed of the liquid to the sponge.

9. In a cleaning device, a body member comprising a bottom, inner and outer side walls, top walls extending between the inner and outer walls and coacting therewith to define a reservoir, the inner walls defining a holder, one of said inner walls being spaced from its corresponding outer wall to provide a supply reservoir, the other inner walls being spaced from their corresponding outer walls to define a passage opening to said supply reservoir, the edge of said supply reservoir inner wall being spaced from the bottom to provide a narrow elongated opening therebetween, the other inner walls having relatively restricted openings for discharging fluid to the holder, said slot-like opening and said reservoir openings being positioned at the top of the holder when the holder is facing downwardly, a baffle disposed in said supply reservoir in spaced relation to its said inner wall and projecting from said bottom, and a handle pivotally

connected to the body member so that when the body member is suspended from the handle the end thereof containing the supply reservoir swings downwardly.

10. In a cleaning device, a body member comprising a bottom, inner and outer side walls, top walls extending between the inner and outer walls and coacting therewith to define a reservoir, the inner walls defining a holder, one of said inner walls being spaced from its corresponding outer wall to provide a supply reservoir, the other inner walls being spaced from their corresponding outer walls to define a passage opening to said supply reservoir, said supply reservoir inner wall being spaced from the bottom to provide a narrow elongated opening therebetween, the other inner walls having relatively restricted openings for discharging fluid to the holder, said narrow elongated opening and said reservoir openings being positioned at the top of the holder when the holder is facing downwardly and in either position of the device opening to said holder and a baffle disposed in said supply reservoir in spaced relation to its said inner wall and protecting from said bottom.
